UNITED STATES PATENT OFFICE.

NELSON C. DURAND, OF NEWARK, NEW JERSEY, ASSIGNOR, BY MESNE ASSIGNMENTS,
TO NEW JERSEY PATENT COMPANY, OF WEST ORANGE, NEW JERSEY, A CORPOR-
ATION OF NEW JERSEY.

DICTION MEMORANDUM-SHEET.

1,098,100.

Specification of Letters Patent.

Patented May 26, 1914.

Application filed December 2, 1911. Serial No. 663,563.

To all whom it may concern:

Be it known that I, NELSON C. DURAND, a citizen of the United States, and a resident of Newark, in the county of Essex and State 5 of New Jersey, have invented a certain new and useful Improvement in Dictation Memorandum-Sheets, of which the following is a description.

My invention relates to memorandum 10 sheets adapted for use in connection with commercial talking machines. Sheets of this type have heretofore been made up into pads and have been made of paper each sheet being destroyed after a single use thereof. 15 For this reason, these sheets have been comparatively expensive and have caused considerable trouble in maintaining a sufficient stock or supply thereof on hand.

It is one of the objects of my invention to 20 obviate these objections by the provision of a memorandum sheet so constructed as to be capable of use a large number of times.

Another object of my invention is to provide an improved sheet of this character by 25 which more conveniently arranged instructions may be given to the transcriber as to the condition of the dictated work than has heretofore been possible.

Other objects of my invention will appear 30 more fully in the following specification and appended claims.

In order that my invention may be better understood, attention is hereby directed to the accompanying drawing forming a part 35 of this specification and in which—

Figure 1 represents a plane or face view 40 of a memorandum sheet embodying one form of my invention; and Fig. 2 represents a cross section thereof taken on the line 2—2 of Fig. 1.

The sheet which is illustrated in the drawing is formed of a central portion 1 of suitable material such as a sheet of celluloid, adapted to receive printed matter, a trans- 45 parent protective covering 2 of material im- pervious to moisture, such as a sheet of celluloid, superposed upon the face of the portion 1, and a backing 3 of a suitable fabric adapted to prevent cracking or break- 50 ing of the sheet during flexure thereof. The memorandum sheet may obviously be made of any suitable size and shape, the parts 1, 2, and 3 thereof being cemented or other-

wise secured together, preferably under pressure.

The portion 1 of my improved sheet carries adjacent the upper edge thereof, a representation 4 of the scale commonly placed on commercial talking machines to indicate the position of the recorder or reproducer with respect to the surface of the blank or record. (See U. S. Patent 772,485 to Weber and Hibbard). Below the scale 4 on sheet 1 is an area subdivided by a number of lines 5 parallel to the scale 4 60 into a plurality of spaces running parallel to the said scale and throughout the length thereof. Each of these spaces contains a stock phrase for designating the particular memorandum or instruction to be noted 65 therein. On one side of the scale and of the above named spaces, the sheet 1 has a number of spaces for data identifying the record.

The stock phrases which are shown on the drawing are "Length," "Carbons," 75 "Corrections," "Rush," "Enclosures". These phrases may, of course, be varied or replaced by others as is found more convenient. The data identifying the record for which a special provision is made on the sheet as shown 80 in the drawing, are the numbers of the record with which the memorandum is used and of the records from and to which the said record is continued, the person who dictated what is recorded upon the record, 85 the person by whom the same is transcribed, and the date and hour.

In using the above memorandum, the dictator if, for example, he wishes to note that corrections have been made in a particular 90 part of the record, draws a vertical line below the proper graduation on the scale in the space designated "Corrections". In transcribing the record, the attention of the operator will accordingly be directed in ad- 95 vance by the memorandum to the place where the corrections are to be made; so that danger of mistakes is avoided. Similarly, if it is desired to rush a letter extending between two particular graduations on the 100 scale, lines are drawn under these graduations in the space marked "Rush" whereby the matter to be rushed will be conveniently indicated to the transcriber. In similar manner, various other instructions may be 105 given to the transcriber. In order to pre-

vent the pencil or other marker from running over from one space to another in marking the sheet, I preferably provide the upper member 2 with a plurality of ribs 6 located above the lines 5 in register therewith. As shown in the drawing, the ribs extend into the member 1. One of the memorandum sheets described above is preferably used with each record cylinder, the sheet being preferably so proportioned as to be adapted for insertion into the bore of the cylinder. When the record has been transcribed, the marks thereon are deleted or cleaned off with a moist cloth or other moistened device and the sheet inserted for reuse into the cylinder. This operation may be conveniently performed by the operator who shaves the cylinder.

With my improved memorandum sheet, the operator has a vivid impression of the memoranda to be noted in transcribing the record and the convenience of the person dictating is greatly increased. While I have shown the preferred form of my improved device, it is obvious that many modifications may be made therein without departing from the spirit of my invention.

What I claim as new and desire to protect by Letters Patent is as follows:

1. A memorandum for talking machines, comprising a sheet carrying the representation of the scale of the talking machine and having at one side of said representation an area subdivided by a number of parallel lines into a plurality of spaces extending parallel to said representation throughout the length of the same, each of said spaces bearing a stock phrase designating a memorandum to be noted therein, substantially as described.

2. A memorandum for talking machines, comprising a sheet of celluloid carrying the representation of the scale of the talking machine and properly designated spaces for entering data identifying the talking machine record, and the persons using the same, and having at one side of said representation an area subdivided by a number of parallel lines into a plurality of spaces extending parallel to said representation throughout the length of the same, each of said spaces bearing a stock phrase for designating the memorandum to be noted therein, substantially as described.

3. A memorandum for talking machines, comprising a sheet carrying the representation of the scale of the talking machine and having at one side of said representation an area subdivided by a number of parallel ribs into a plurality of spaces extending parallel to said representation throughout the length of the same, each of said spaces bearing a stock phrase for designating the memorandum to be noted therein, substantially as described.

4. A memorandum for talking machines, comprising a sheet of celluloid carrying the representation of the scale of the talking machine and having at one side of said representation an area subdivided by a number of parallel ribs into a plurality of spaces extending parallel to said representation throughout the length of the same, each of said spaces bearing a stock phrase for designating the memorandum to be noted therein, substantially as described.

5. A memorandum for talking machines, comprising a sheet carrying the representation of the scale of the talking machine and having at one side of said representation an area subdivided by a number of parallel lines into a plurality of spaces extending throughout the length of said representation, each of said spaces bearing a stock phrase for designating the memorandum to be noted therein, and a protective covering of transparent material secured to the face of said sheet over said representation, lines, and stock phrases, substantially as described.

6. A memorandum for talking machines, comprising a sheet carrying the representation of the scale of the talking machine and having at one side of said representation an area subdivided by a number of parallel lines into a plurality of spaces extending throughout the length of said representation, each of said spaces bearing a stock phrase for designating the memorandum to be noted therein, and a protective covering of transparent material secured to the face of said sheet, said covering being formed with a plurality of ribs, in register with the lines on the said sheet, substantially as described.

7. A memorandum for talking machines, comprising a sheet carrying the representation of the scale of the talking machine and having at one side of said representation an area subdivided by a number of parallel lines into a plurality of spaces extending throughout the length of said representation, each of said spaces bearing a stock phrase for designating the memorandum to be noted therein, and a covering of transparent material impervious to moisture secured to the face of said first named sheet, said covering being formed with a plurality of ribs in register with the lines on said sheet, and a fabric backing cemented to the back of said sheet, substantially as described.

8. A memorandum for talking machines, comprising a sheet carrying the representation of the scale of the talking machine and having at one side of said representation an area subdivided by a number of parallel ribs into a plurality of spaces extending parallel to said representation throughout the length of the same, substantially as described.

9. A memorandum for talking machines comprising a sheet having on the face thereof the representation of the scale of the talking machine and at one side of said representation an area for memoranda, a transparent layer of protective material secured to and covering the face of said sheet, and a fabric backing secured to the back of said sheet, substantially as described.
10. 10. A memorandum for talking machines, comprising a sheet having on the face thereof the representation of the scale of the talking machine and at one side of said representation an area for memoranda, a transparent layer of celluloid secured to and covering the face of said sheet, and a fabric backing secured to the back of said sheet, substantially as described.
11. A memorandum for talking machines, comprising a sheet carrying the representation of the scale of the talking machine and
- 15 having at one side of said representation an area divided by a rib into a plurality of spaces extending parallel to said representation throughout the length of the same, substantially as described. 25
12. A memorandum for talking machines, comprising a sheet carrying the representation of the scale of the talking machine and having at one side of said representation an area divided by a rib into a plurality of spaces extending parallel to said representation throughout the length of the same, each of said spaces bearing a stock phrase for designating the memorandum to be noted 30 35 therein, substantially as described.

This specification signed and witnessed this 29th day of November 1911.

NELSON C. DURAND.
